[57] CLAIM

The ornamental design for a public seating chair, as shown and described.

DESCRIPTION

FIG. 1 is a top plan view showing a main embodiment of the invention;

FIG. 2 is a bottom plan view thereof;

FIG. 3 is a front elevation view thereof;

FIG. 4 is a rear elevation view thereof;

FIG. 5 is a left side elevation thereof, the right side elevation being a mirror image thereof;

FIG. 6 is a left front perspective thereof;

FIG. 7 is a left front perspective thereof, with the seat component rotated to a non-use position;

FIG. 8 is a rear elevation of a second embodiment of the invention; and,

FIG. 9 is a front elevation of the second embodiment, with the seat component raised to a non-use position.

*FIG. 2**FIG. 1**FIG. 4**FIG. 3**FIG. 8**FIG. 5*FIG. 7

FIG. 6

FIG. 9
